(57) CLAIM

The ornamental design for a cartridge for skin treatment device, as shown and described.

DESCRIPTION

FIG. 1 is a front, perspective view of a cartridge for skin treatment device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an exploded, perspective view thereof, together with an unclaimed nozzle cap.

The broken lines illustrate structure or features which form no part of the claimed design.

The drawings include surface shading which illustrates contour and not surface ornamentation.
